UNITED STATES PATENT OFFICE.

COMMODORE P. HELLYER, OF RUSSELL, IOWA.

DRAG-SAW MOTOR.

SPECIFICATION forming part of Letters Patent No. 660,955, dated October 30, 1900.

Application filed June 4, 1900. Serial No. 19,039. (No model.)

To all whom it may concern:

Be it known that I, COMMODORE P. HELLYER, a citizen of the United States, residing at Russell, in the county of Lucas and State of Iowa, have invented certain new and useful Improvements in Drag-Saw Motors, of which the following is a specification.

My invention relates to improvements in drag-saw motors, all of which will be fully described hereinafter and particularly pointed out in the claim.

The object of my invention is to provide a mechanism by means of which a drag-saw can be rapidly operated and by means of which it can also be raised and lowered in respect to the object being sawed.

In the accompanying drawings, Figure 1 is a side elevation of a motor embodying my invention. Fig. 2 is a top plan view of the same. Fig. 3 is a side elevation looking at the opposite side from that shown in Fig. 1.

Referring now to the drawings, A is a rectangular frame in which my mechanism is supported. Journalized in the front end of the frame is a horizontal shaft B, carrying at one end a crank C, to which one end of a pitman D is pivotally connected. The opposite end of this pitman D is pivotally connected to an operating-lever E at the point F, which is intermediate the ends of the said lever E. From this it will be seen that when the upper free end of the lever E, which has its lower end pivotally connected at the point F', is reciprocated the shaft B is rotated.

Secured to the shaft B is a pulley G, around which passes a belt or chain H, the said belt or chain H passing also around a smaller pulley I, which is fast to a crank-shaft J. This crank-shaft J has a crank K intermediate its ends and carries a balance or fly wheel L.

Projecting vertically and situated at a point intermediate the front end of the frame A is a suitable standard M, and having one end connected with the said standard M is a bar N, the opposite end of the bar N being connected with the frame A. A lever P is intermediately pivoted to the bar N near its front end, and connecting the front end of this lever P and the crank K of the shaft J is a pitman Q. Pivots connected with the oppo-

site end of the lever P is a saw carrying pitman R, the outer end S being suitably constructed to receive the saw T. This saw-pitman R consists of two parallel separated bars 55 situated at opposite sides of the vertical standard M and also at opposite sides of a vertical rod a. The lower end of this rod a, which serves as a means for raising and lowering the saw-pitman R, is pivotally connected with 60 a lever b, the opposite and inner end of the said lever being pivotally connected in any suitable manner with the frame A. From this description it will be seen that the saw-pitman R rests upon the lever b and is supported thereby, while it is guided in its movements through the medium of the standard M and the bar a. The upper end of the bar a is pivotally connected with the outer end of the intermediately pivotally supported lever c, the said lever c serving as means for raising and lowering the lever b, and hence in turn raising and lowering the saw-pitman R, and consequently the saw. 70

The handle end of the lever c extends to 75 the rear portion of the machine, whereby the operator can operate the lever E with one hand for causing the reciprocation of the saw and with the other (preferably the left hand) grasp the hand end of the lever c for raising and 80 lowering the saw through the medium of the saw-pitman R, as before explained.

For the purpose of assisting in guiding the saw a lever d has its inner end pivotally connected with the standard M and has its outer 85 end provided with a downwardly-projecting fork e, which straddles the upper edge of the saw T. This guiding-lever d passes loosely through a loop f upon the rod a.

From this description it will be seen that 90 the operator can cause a rapid reciprocation of the saw with one hand, while with the other hand he can regulate the engagement thereof with the object being sawed.

Having thus described my invention, what 95 I claim, and desire to secure by Letters Patent, is—

In a drag-saw the combination with a saw and a reciprocating mechanism operatively connected therewith, of a lever b for lifting 100 the saw, a lever c operatively connected with the lever b through the medium of the verti-

cal bar *a*, and a guiding-bar *d* having its inner end pivotally connected and its outer end provided with a fork engaging the top edge of the saw, the bar *d* being intermediately but slidably connected with the bar *a*, whereby when the saw is lifted the guiding-bar *d* is also lifted, substantially as described.

In testimony whereof I affix my signature in presence of two witnesses.

COMMODORE P. HELLYER.
